ROUTING MACHINE

Arvid Bjorklund, Minneapolis, Minn.

Application December 27, 1948, Serial No. 67,421

11 Claims. (Cl. 144—136)

1

My present invention relates to a highly efficient routing machine that is easy to operate and adjust for general use in various different kinds of routing work, and is especially well adapted for use in making core boxes.

To the above end, the invention consists of the novel devices and combination of devices herein-after described and defined in the claims.

In the accompanying drawings, which illustrate the invention, like characters indicate like parts throughout the several views.

Referring to the drawings:

Fig. 1 is a front elevational view of the improved machine;

Fig. 2 is a side elevational view of the same;

Fig. 3 is a rear elevational view;

Fig. 4 is a top plan view;

Fig. 5 is a view principally in section, taken on the line 5—5 of Fig. 2;

Fig. 6 is a detail view principally in section, taken on the line 6—6 of Fig. 1;

Fig. 7 is a fragmentary detail view partly in elevation and partly in section, taken on the line 7—7 of Fig. 1;

Fig. 8 is a view principally in plan, with some parts sectioned on the line 8—8 of Fig. 2;

Fig. 9 is a fragmentary view partly in front elevation and partly in section, taken on the line 9—9 of Fig. 8;

Fig. 10 is a view of the main base and frame, as shown in Fig. 8, mounted on a piece of work, and a rail pivoted to said work;

Fig. 11 is a side view of the parts shown in Fig. 10, and

Fig. 12 is a fragmentary front elevational view of the parts shown in Fig. 10.

The numeral 10 indicates a rectangular sub-base in the form of a flat plate having on its top an annular track rail 11. A turnplate 12 is mounted on the sub-base 10 and has in its under side, an annular groove 13 into which the track rail 11 extends, and holds the turnplate 12 for turning movement about the axis of said track rail. A pair of parallel track rails 14 are secured in a groove 15 in the upper face of the side portions of the turnplate 12. Supported on the turnplate 12 is a main base 16 in the form of a flat plate having in its under side, grooves 17, into which the track rails 14 extend and hold said main base for straight line sliding movement on the turnplate 12. The distance between the track rails 14, corresponds substantially to the diameter of the track rail 11. The turnplate 12, and the main base 16, are of substantially the same size and contour, and the sub-base extends materially

forwardly and rearwardly of said turnplate and main base. In the central portions of the sub-base 10, the turnplate 12 and the main base 16, are aligned work and sight apertures 18, 19, and 20, respectively.

On the underside of the sub-base 10, at the sides thereof, is a pair of laterally spaced angle bars 21. Two of the flanges 22 of the angle bars 21 are turned toward each other and have flat contact with the under side of the sub-base 10, and the other two flanges of said angle bars extend downwardly and afford a pair of guides 23. The angle bars 21 are secured to the sub-base 10 for adjustment toward and from each other to vary the distance between the guides 23 by front and rear pairs of studs 24 equipped with thumb nuts 25. These studs 24 extend through transverse slots 26 in the sub-base 10, and the thumb nuts 25 impinge the top of said sub-base.

Integral with the main base 16 is an upright frame 27 that extends transversely thereof. This frame 27 is in the form of a flat plate reinforced by a pair of front ribs 28 and a pair of rear ribs 29. These ribs 28 and 29 are integral with the main base 16 and the frame 27. Formed in the frame 27, at its transverse center, is a wide opening 31, open at its lower end, and above this opening 31 is a narrower opening 32 that forms a continuation of the opening 31. The vertical edge portions of the frame 27, at the opening 32, are thickened to afford ways 33. A vertical slide 34 is mounted in the opening 32 and has in its sides channels 35 into which the ways 33 extend. This slide 34 is raised or lowered on the ways 33 by a long upright screw rod 36 having threaded engagement with a nut-acting member 37 integral with the frame 27 at the back thereof and above the opening 32. The screw rod 36, at its lower end is attached, to permit swiveling movement, to the slide 34 at its upper end, and on the upper end of said rod is a hand wheel 38.

An electric motor 39 is held, with its axis in an upright position, in a wide clamp 40 comprising a body member 41, and a pair of semi-cylindrical jaws 42. The body member 41 has a flat back and the jaws 42, have on their free ends, outturned flanges 43 that are spaced apart. These flanges 43 are adjustably connected by a pair of machine screws 44. This clamp 40 is slidably mounted on a pair of laterally spaced upright guide rods 45 that are in a vertical plane parallel to the flat back of the clamp body member 41. The armature shaft 46 of the motor 39 is in a depending position within the apertures 18, 19, and 20, and attached thereto is a cutter

47. By loosening the clamp 40 the motor 39 may be raised or lowered therein.

The guide rods 45, at their upper end portions, extend through holes in bosses 48 integral with the vertical face of a slide 49 in the form of a long rectangular bar. This slide 49 is mounted in a horizontal channel 50 in front of the frame 27 at the top thereof. The guide rods 45 are secured to the slide 49 by pairs of opposing nuts 51 that impinge opposite sides of the bosses 48. The clamp 40 is supported in part, on a pair of coiled springs 52 encircling the guide rods 45 and rest on washers 53 held by nuts 54 applied to the lower end portions of said rods. These springs 52, at their upper end portions, are counter-sunk in deep holes 55 in the under side of the clamp body member 41.

The slide 49 is held in the channel for straight line sliding movement by a knurled thumb screw 56 that extends through a longitudinal slot 57 in the top of the frame 27 and has threaded engagement with said slide. By tightening the thumb screw 56, the slide 49 may be locked relative to the frame 27 in different endwise adjustments. The clamp 40 may be secured in different vertical adjustments on the guide rods 45 by a knurled thumb screw 58 that has threaded engagement with the clamp 40 for impinging one of the guide rods 45.

On the back of the clamp member 41 is a stud 59 that extends into a hole 60 in one end portion of a radius slide 61 mounted on a cross-head 62 rigidly secured to the front end of a shaft 63 journaled in the slide 34 at its center. The slide 61 is adjusted on the cross-head 62 by a long screw rod 64 that has threaded engagement with a nut-acting lug 65 on the cross-head 62 that extends into a slot 66 in the slide 61 on the opposite side of the shaft 63 from the stud 59. This screw rod 64 is turnably mounted in the opposite end portion of the slide 61 from the stud 59 and is held therein against endwise movement by a knurled head 67 and a fixed collar 68 on the screw rod 64. The screw rod 64, at its inner end, is turnably mounted in the slide 61 at the inner end of the slot 66. Obviously, by manipulating the screw rod 64, the slide 61 may be moved on the cross-head 62 to vary the length of the radius between the axes of the stud 59 and the shaft 63.

On the outer end portion of the shaft 63 is a hand wheel 69 secured thereto by a set-screw 70 having threaded engagement with the hub of said hand wheel and impinging the shaft 63.

Mounted on the shaft 63 between the slide 34 and the hand wheel 69 is a worm gear 71 that is turned by a worm 72 on a shaft 73 between bearings 74 in which said shaft is journaled. These bearings 74 are integral with the slide 34 and a hand wheel 75 is applied to the outer end of the shaft 73. The worm gear 71 is releasably secured to the shaft 63 by a set-screw 76 that has threaded engagement with the hub of said worm gear. Obviously, the shaft 63 may be turned by the hand wheel 69 when the worm gear 71 is loose on the shaft 63, or it may be turned by the hand wheel 75 when the worm gear 71 is fast on the shaft 63.

On the front ribs 28 is a pair of handles 77 in the form of knobs by which the improved routing machine may be manipulated relative to a piece of work. In the drawings, as shown, the machine is supported on a piece of work in the form of a block of wood *x* in which a concave cut *y* has been made by the cutter 47. The horizontal flanges 22 of the angle bars 21 slidably rest 75

on the work *x* and the guide flanges 23 are closely positioned to the sides of said work to guide the machine for straight line sliding movement on said work.

5 In Fig. 10, the main base 16, as shown in Fig. 8, has been removed from the turnplate 12 and slidably mounted on a piece of work *z*, and a rail 78 similar to one of the rails 14. This rail 78 extends into the left hand way 17 in the main base 16 and is pivotally attached at its rear end portion to the work *z* by a screw 79. Obviously, by swinging the rail 78 on its pivot screw 79, the cutter 47 will be moved transversely of the work *z* in the arc of a circle. By sliding the main base 16 longitudinally on the rail 78, the length of the radius from the center of the screw 79 to the axis of the cutter 47 may be varied at will. To secure the main base 16 in different longitudinal adjustments on the rail 78, a set-screw 80 is provided. This set-screw 80 has threaded engagement with the main base 16 and when tightened, impinges the rail 78. To move the main base 16 in a predetermined straight line, the rail 78 is secured against pivotal movement by a second screw 81, indicated by broken lines in Fig. 10. This set-screw 81 extends through a hole 82 in the opposite end portion of the rail 78 from the screw 79 and has threaded engagement with the work *z*.

30 What I claim is:

1. In a machine of the class described, a base, a frame on the base, a vertical slide on the frame, screw means for raising or lowering the slide, a shaft journaled in the slide, and having a cross-head, means for turning the shaft, a second slide on the cross-head, means for adjusting said second slide on the cross-head, a motor support pivoted on the second slide, means movable with the second slide for guiding the motor support, an electric motor attached to the motor support, and a tool on the armature shaft of the motor.

2. In a machine of the class described, a base, a frame on the base, a vertical slide on the frame, a screw means for raising or lowering the slide, a shaft journaled in the slide, and having a cross-head, means for turning the shaft, a second slide on the cross-head, screw means for adjusting the second slide on the cross-head, a motor support pivoted on the second slide, sliding means on the frame for guiding the motor support, an electric motor attached to the motor support, and a tool on the armature shaft of the motor.

3. In a machine of the class described, a base, a transverse frame on the base having a central upright opening and ways at the side of said opening, a slide mounted on the ways, a hand wheel equipped screw rod having threaded engagement with a nut acting member on the frame and turnably attached to the slide, a shaft journaled in the slide and having a cross-head, a second slide mounted on the cross-head, screw means for adjusting the second slide on the cross-head, means for turning the shaft, a motor support pivoted on the second slide, said frame having a channel, a third slide mounted in the channel and having a pair of depending guide rods on which the motor support is slidably mounted, an electric motor attached to the motor support, and a tool on the armature shaft of the motor.

4. The structure defined in claim 3, further including means for locking the motor support relative to the guide rods.

5. The structure defined in claim 1 further including a guide rail with which the base has sliding interlocking engagement.

6. The structure defined in claim 1 further including a guide rail with which the base has sliding interlocking engagement, and means for locking the base relative to the guide rail.

7. The structure defined in claim 1 further including a guide rail with which the base has sliding interlocking engagement, said guide rail being angularly adjustable.

8. In a machine of the class described, a frame having a base, an electric motor mounted on the frame, a shaping tool on the armature shaft of the motor, a guide rail mounted directly on a piece of work, and means detachably securing the guide rail directly to the piece of work, said base having in its under side a groove open at its ends, said guide rail extending longitudinally through the groove with the base slidably resting on the piece of work, the sides of the groove having a working fit with the sides of the guide rail.

9. The structure defined in claim 8 in which the means for removably securing the guide rail to the piece of work is a screw at each end portion of the guide rail whereby one of the screws may be removed and the guide rail swung about the axis of the other screw to move the base on the arc of a circle.

10. The structure defined in claim 8 in which the guide rail is rectangular in cross-section.

11. The structure defined in claim 8, further including a set-screw having threaded engagement with the base at one of its sides and impinging the guide rail.

ARVID BJORKLUND.
